S. R. BAILEY, OF BATH, MAINE.

Letters Patent No. 85,896, dated January 19, 1869.

IMPROVED SLEIGH-BOTTOM.

The Schedule referred to in these Letters Patent and making part of the same.

To all to whom these presents shall come:

Be it known that I, S. R. BAILEY, of Bath, in the county of Sagadahoc, and State of Maine, have made an invention of certain new and useful Improvements in the Manufacture of Sleigh-Bottoms, which I term a truss-flooring; and do hereby declare the following to be a full, clear, and exact description thereof, due reference being had to the accompanying drawings, making part of this specification, and in which—

Figure 1 is an under-side view,

Figure 2, a vertical and longitudinal section, and

Figure 3, a transverse section of the lower part or flooring of a sleigh containing my improved construction.

As heretofore constructed, the flooring of a sleigh has been secured to its side rails by simply securing the boards of the floor, at their ends, to the under side of the side rails of such floor, and subsequently applying a thin, narrow strap of iron over the outer surface of the bottom, from front to rear thereof, for the purpose of stiffening the flooring to some extent, which, however, proves to be of little effect.

A flooring thus made is capable of sustaining comparatively little weight, and the lateral thrusts and concussions to which sleighs are subject often separate it from the body.

My invention relates to means whereby to produce a flooring for a sleigh-body, which shall possess the characteristics of lightness, strength, and durability, without adding to the expense thereof; and consists, first, in extending a series of bars or strips of wood, lengthwise of and from end to end of the sleigh-bottom, and between its side rails, and resting upon the top of the cross-bars which support the bottom upon the runners; and secondly, in applying the flooring in a suitable manner to the upper surface of these longitudinal strips, the whole being as hereinafter explained.

In the drawings above mentioned as illustrating my invention—

a a denote the side rails of a sleigh-body, and *b b*, &c., the cross-bars upon which they rest, such parts being combined together in the ordinary manner, it being understood that the cross-bars *b b* are affixed to and rest upon the standards or uprights making part of the runners, as common to sleighs now in use.

In carrying out my invention, I apply and secure to the upper surface of the cross-bar *b b*, and extending longitudinally from the front to the rear one thereof, and at suitable intervals between the side rails, to which they about correspond in length, a number of strips, *c*

c c, &c., of wood, or stringers, and steam them, and to the upper surface of these stringers, and crosswise of the same, I apply the boards *d d*, &c., composing the sleigh-bottom, such boards being confined to the side rails and to the stringers by screw-rivets, or in any suitable manner, it being provided that a small space, *e*, is left between the extreme ends of the boards *d d*, and the outer edge of the side rails *a a*, as shown in fig. 3 of the drawings.

The width of this space is about equal to the thickness of the sides of the sleigh-body, which extend into it, thus making a close joint, and giving a highly-finished appearance to the sleigh.

Another advantage of the space *e* is, that by means of it the bottom boards conceal the inner lower edge of the side of the body, and the tacks which confine the upholstering to such side.

As this concealment is accomplished without trouble, other than to place the sleigh-body in its proper position, the latter may be taken off at any time without trouble or injury. Other advantages resulting from them, applying the bottom to the side rail, will manifest themselves to persons familiar with the manufacture of sleighs.

By the above construction of parts, I claim that I form, substantially, a truss-frame, to resist any lateral thrust or concussion to which a sleigh is subject, while it will be apparent that, as the bottom is applied to the upper surface of the side rails, and the cross-bars, that breakage, or loosening, or misplacement of the flooring is impossible, while the whole sleigh-bottom is vastly stronger and more durable than at present constructed.

Claim.

I claim as my invention, and desire to secure by Letters Patent of the United States—

The improved construction of sleigh-bodies as herein represented and explained, that is, the employment of the stringers *c c*, applied in connection with the side rails *a a* and the cross-bars *b b*, and supporting upon their upper surfaces the bottom boards *d d*, &c., the latter being so applied to the side rails *a a* as to leave the "jog" or space *e*, and the whole being arranged in manner and productive of advantages as hereinbefore referred to and shown.

S. R. BAILEY.
